UNITED STATES PATENT OFFICE.

HENRY H. RUSSELL, OF NEW YORK, N. Y., ASSIGNOR TO WALTER D. HODSON, OF JAMESVILLE, WISCONSIN.

ELECTRICAL HEATING UNIT.

1,071,350.

Specification of Letters Patent. Patented Aug. 26, 1913.

Application filed April 6, 1911. Serial No. 619,231.

To all whom it may concern:

Be it known that I, HENRY H. RUSSELL, a citizen of the United States, residing at New York, county of New York, and State 5 of New York, have invented a certain new and useful Improvement in Electrical Heating Units, of which the following is a specification.

My invention relates to improvements in 10 electrical heating units such as may for instance be used in connection with the usual fireless cooker. It is illustrated diagrammatically in one form in the accompanying drawing wherein—

15 Figure 1 is a plan view of the device. Fig. 2 is a section along the line 2—2 of Fig. 1. Fig. 3 is a plan view of the unit with the top removed. Fig. 4 is a view similar to that shown in Fig. 3 of a modified form.

20 Like parts are indicated by like letters in all the figures.

The heating unit A, which is provided with the usual recess A¹, containing the lifting ring A², is perforated at A³ and is made 25 up of two more or less similar flat disks B, B¹, and held together by the cement B². The flat resistance wire B³ which is bent back and forth radially within the unit A is embedded within the cement B² and terminates at either end in the conducting sleeve B⁴, which is embedded in the plates B, B¹ and concentric with the perforations A³, and contains the spring member B⁵. In 30 the modified form illustrated in Fig. 4 the resistance wire C is wound spirally about the thin, flat, insulating plate C¹ which is contained between similar disks C², but one of which is shown, and terminates in similar sleeves C³ in the perforations C⁴.

40 It will be evident that while I have shown in my drawing an operative device, still many changes might be made, both in size, shape and arrangement of parts, without departing materially from the spirit of my invention and I wish, therefore, that my drawing be regarded as in a sense diagrammatic.

45 The use and operation of my invention are as follows: When it is desired to heat the radiator, the terminal sleeves which are embedded within the body of the plate are connected up to any suitable source of electric power by certain means, not here shown, whereby live terminals are introduced into 50 the perforations in the disk and brought in

contact with the embedded sleeves. The current passing through the resistance wire soon brings it to a relatively high heat and thoroughly heats the radiator from the interior outwardly. The result is to provide 60 a radiator which is evenly heated and in which the path of the heat is never reversed, as it is in the case of the radiator which is first heated from the outside in and then gives off its heat from the inside out. By 65 providing the embedded contacts or terminals, I make use of some particular apparatus for the heating of the device, thus preventing risk of fire by the heating of the device at some unsuitable time or place, that 70 is to say, if it were possible by using any ordinary conducting wires connected up at one end to the source of power and connected up at the other to the exposed terminals on the radiator, a careless operator might 75 throw on the current and heat up the radiator when it was in contact with inflammable substances. If then he should neglect it for a few moments it would heat up to such 80 temperature as to set these substances on fire and cause considerable damage. This of course, could not be done when the device is arranged as I have indicated because it is impossible to connect the terminals to the 85 source of power until they are brought into proper relation with some receptacle or apparatus which is designed to prevent danger from fire caused by overheating of the exposed radiator.

It will be evident that in view of the fact 90 that the radiator is heated from the inside outwardly instead of from the outside inwardly, the heating may be done in this manner with a very much higher efficiency 95 and less loss in view of the fact that all of the heat which is generated in the radiator must pass through it and heat it and is not therefore wasted, as is the case when a very large amount of heat is applied to the outside, a large percentage of which is of course 100 wasted and passes away without ever coming in contact with the radiator.

The terminal conducting sleeves are embedded within the heating unit, being free 105 to move about within it, although of course being limited in their motion. The purpose of this is to prevent any cracking or distortion or jamming or locking of the parts when heat is applied, such as might take place owing to the possible different coeffi- 110

lients of expansion of the heating unit, the sleeves themselves and the electrodes which must be inserted to couple the heating coil with the source of electrical power. The 5 looseness of the sleeves also permits them to adjust themselves to any inequalities or irregularities in size, shape and arrangement of the electrodes which may be introduced into the terminal sleeves.

10 I claim:

1. A heating element for fireless cookers and the like comprising a pair of flat disks, an electric resistance coil interposed between said flat disks, said disks and said coil being rigidly held together in position, said disks being perforated, the perforations in said disks being in line with each other to form a passage completely through the element, said passage being of constantly diminishing cross sectional area from the surface of the element inwardly, and terminal sleeves located one in each of said perfora-

tions of smaller diameter than the passage at the surface of the disks, said sleeves being electrically connected one to each terminal 25 of the heating unit, said sleeves terminating on either side below the surface of the heating element.

2. A heating element for fireless cookers and the like comprising a flat disk, an electric heating resistance unit located therein, said disk having two perforations, and terminal sleeves located one in each perforation, said sleeves being electrically connected one to each terminal of the electric heating 30 unit, said sleeves being concentric with the perforations and terminating on either end below the surface of the disk.

Mch. 29, 1911.

HENRY H. RUSSELL.
